(57) **CLAIM**

The ornamental design for a lighting device, as shown and described.

DESCRIPTION

FIG. 1 is a perspective view of the lighting device;
 FIG. 2 is another perspective view of the lighting device;
 FIG. 3 is a rear view of the lighting device;
 FIG. 4 is a front view of the lighting device;
 FIG. 5 is a left side view of the lighting device;
 FIG. 6 is a right side view of the lighting device;
 FIG. 7 is a top view of the lighting device; and,
 FIG. 8 is a bottom view of the lighting device.
 The broken lines in the drawing depict portions of the lighting device that form no part of the claimed design.
